UNITED STATES PATENT OFFICE

158,661

BRACELET

Comfort Genevieve Holland Harris,
Baltimore, Md.

Application August 24, 1949, Serial No. 4,673

Term of patent 14 years

(Cl. D45—4)

To all whom it may concern:

Be it known that I, Comfort Genevieve Holland Harris, a citizen of the United States, residing at Baltimore, in the State of Maryland, have invented a new, original, and ornamental Design for a Bracelet, of which the following is a specification, reference being had to the accompanying drawing, forming part thereof.

Fig. 1 is a side perspective view of a bracelet showing my new design;

Fig. 2 is a front perspective view thereof; and

Fig. 3 is a rear perspective view of the bracelet with the chain element omitted for convenience of illustration.

I claim:

The ornamental design for a bracelet, as shown.
COMFORT GENEVIEVE HOLLAND HARRIS.
